(57) **CLAIM**

I claim the ornamental design for a lighting fixture with light emitting diode, as shown and described.

DESCRIPTION

FIG. 1 is a bottom perspective view of a lighting fixture with light emitting diode of the present invention;

FIG. 2 is a right side view thereof, wherein the left side view is a mirror image thereof;

FIG. 3 is a front view thereof, wherein the rear view is a mirror image thereof;

FIG. 4 is a top view thereof; and,

FIG. 5 is a bottom view thereof.

The broken line showing of the environment is for illustrative purposes only and forms no part of the claimed design.
